UNITED STATES PATENT OFFICE

LOUIS A. NEMCOVSKY, OF NEW YORK, N. Y., ASSIGNOR, BY MESNE ASSIGNMENTS, TO MARGON CORPORATION, OF NEW YORK, N. Y., A CORPORATION OF NEW YORK

EYE SET

Original application filed July 14, 1925, Serial No. 43,438. Divided and this application filed May 7, 1927, Serial No. 189,612. Renewed March 26, 1931.

My present invention relates primarily to dolls having mechanism for movable elements such as eyes, and has particular reference to a construction and method of assembly and installation of such mechanism and of a supporting device therefor.

This is a division of my pending application Serial Number 43,438, filed July 14th, 1925.

10 An object of the invention is to provide a mechanism of the type referred to which will consist of relatively few parts of simple construction; which will be inexpensive to manufacture; which will require the least expenditure of time and skill to assemble and install; and which will at the same time be staunch and efficient in operation.

Another object is to provide a mechanism and a supporting device therefor, which will 20 be suitable for dolls' heads of diverse sizes, shapes, and proportions, and which will adjust and adapt itself to the various irregularities in dolls' heads produced in the course of their manufacture.

25 Another object of the invention is to provide a mechanism of the type referred to which will be insertable and adjustable within the doll's head without the use of special tools or of attaching substances such as cement, solder or the like.

Another object is to provide a supporting device for the movable mechanism which will allow the latter to be independently assembled and installed so as to permit adjustment of the movable elements into correct position, whereupon the supporting device may be inserted and brought into operative position and subsequently adjusted to clamp the mechanism in position.

According to one feature of the invention, the movable mechanism comprises a bridge member having movable elements, such as eyeballs, slidably and rotatably mounted with respect thereto so that these elements may adjust themselves with respect to the distance between them; and the supporting device comprises one or more adjustable bracing members subsequently brought into position and engaging the bridge member therebetween, and means for thereupon ad-

justing the bracing members to clamp the bridge member and secure it in correct adjusted position.

According to another feature of the invention, the supporting device is designed to engage and to be held in position by portions of the wall of the doll head, and means are provided whereby the adjustment of the bracing members will simultaneously clamp the bridge member and more firmly secure the supporting device itself in its position within the doll head.

Another feature of the invention lies in pivotally mounting the bridge member with respect to the supporting device to enable it to rock in an axial plane whereby complete and accurate adjustment of the movable elements to irregularities in the doll head may be facilitated and effected.

In the present embodiment, the relatively movable and adjustable bracing members of the supporting device are insertable into the head in a manner causing them to engage opposite walls of the doll head, preferably by finding footings and biting therein. In this type of construction, certain of the members support the bridge member therebetween and are preferably provided with means for temporarily retaining them in engaged position with the walls of the head. Means are provided for thereupon drawing the members together to clamp the bridge member, and for simultaneously causing adjustment of the members to increase their combined effective length whereby they will bite more firmly and secure a permanent footing in the opposite walls of the doll head.

According to another feature of the invention the bracing members of the type last referred to may comprise a toggle frame consisting of toggle members and a co-operating strut therefor, the mechanism for the movable elements being held firmly between the strut and one of the toggle members. Means, preferably comprising a bolt or the like, co-operate with the strut and the toggle members to cause simultaneous clamping of the mechanism and spreading of the toggle members.

A more detailed object of the present in-

vention therefore is to provide an eye set comprising a pair of eyes, a cross rod connecting said eyes, and a supporting carrier for said cross rod comprising parts movable with respect to each other to bite into opposite wall portions of the doll head or the like for fixing the carrier to the head and thus in turn supporting the eyes in a position to which they were moved prior to the act of fixing the carrier in position.

10 Other objects and aims of the invention, more or less specific than those referred to above, will be in part obvious and in part pointed out in the course of the following description of the elements, combinations, arrangements of parts and applications of principles constituting the invention; and the scope of protection contemplated will be indicated in the appended claims.

15 20 In the accompanying drawings which are to be taken as a part of this specification, and in which I have shown merely a preferred form of embodiment of the invention:—

25 Fig. 1 is a vertical sectional view through a doll head having an eye set in position therein in accordance with this invention,

30 Fig. 2 is a horizontal sectional view taken substantially upon the plane of line II—II of Fig. 1, and

35 Fig. 3 is a fragmentary detail view illustrating a modification of the manner of connecting the eye supporting cross rod with the toggle frame.

40 Referring to the drawings, I have shown a portion of a doll's head 20 having eye sockets 21 therein for the reception of eye balls 25—25.

45 These eye balls are mounted at opposite ends of a bridge member or cross rod 84 and have suitable fastening devices as 27—27 at their rear sides by which they may be connected with a counter-weight frame 28 which carries a weight 53 at its lower end.

50 The means illustrated for supporting the bridge member or cross rod 84 comprises a toggle frame consisting of toggle members 78 and 79 and a supporting element or strut 81 co-operating therewith. I have shown the toggle member 78 as being preferably bifurcated and as provided with a portion 80 connecting the bifurcated portions and provided with a threaded opening therein. The strut 81 underlies the members 78 and 79 and is provided with an elongated opening 82 through which a bolt as 83 or similar means is passed to engage with the threaded opening in the portion 80 of member 78. The forward end of the strut 81 underlies the cross rod 84 and the forward portion of the toggle member 78 overlies the cross rod 84 so that the latter is supported between the strut and the toggle member 78. The rear end of the strut 81 is preferably beat upwardly as at 76 and terminates in a stepped

end 85 engaging the under edge surface of the toggle member 79.

55 The toggle members 78 and 79 are preferably provided with a series of spaced openings as 86—86 therein adjacent their pivoted ends and suitable connecting means, such as a cotter pin or the like as 87, is passed through certain of these openings to pivotally connect the toggle members together at a selected point.

60 I prefer to provide a spring as 88 engaging the toggle members respectively at its ends and passing over the cotter pin 87 for the purpose of preventing total collapse of the toggle frame during its preliminary adjust-

65 70 75 In this embodiment of my invention the eye balls 25—25 are preferably slidably and rotatably mounted upon the cross rod so that they may find their own centres within the eye sockets 21—21 of the doll head and so that they may rotate freely under the impulse of the gravity weight 53 notwithstanding the stationary condition of the cross rod in use.

75 80 85 The assembly and installation of this construction is preferably effected by assembling the eye balls and the counter-weight frame upon the cross rod, then inserting this mechanism or unit into the doll head so that the eye balls engage within their respective sockets. Thereupon the supporting device consisting of the toggle frame and strut is inserted into the head and adjusted into a position to engage the cross rod.

90 95 100 Although if desired the toggle frame and its strut may be connected with the cross rod at the time when the cross rod and its attached parts are inserted, if preferred. In any event, after the eye balls have been placed and the toggle frame is in a correct position, being temporarily held by the spreading ends of the spring 88 against the toggle members urging the ends of the toggle members against opposite wall surfaces of the head, the screw 83 is tightened to cause a simultaneous clamping of the cross rod between the toggle member 78 and the strut 81 and a spreading or extension of the toggle members 78 and 79 to cause the pointed ends at 89 and 90 of said toggle members respectively to press tightly against, 105 and preferably bite into the adjacent opposite wall surfaces of the doll head.

110 115 120 In order to adjust the toggle frame and strut to properly fit into a given doll head certain of the holes 86—86, and certain of the steps of the end 85 of the strut are selected to be operative depending upon the size and proportions of the particular doll head.

125 130 135 The spring 88 serves to hold the entire mechanism in a temporary braced position against the opposite walls of the doll head, and the subsequent manipulation of the bolt 83 will cause simultaneous clamping of the cross rod and spreading apart of the toggle

members to find permanent and secure footing in the doll head walls, the eye balls being thus retained relatively permanently in the position to which they were initially moved with respect to the eye sockets.

It is noted that if desired the eye balls could of course be made to have no movement with respect to the cross rod, or only a sliding movement thereon, in which event 10 the necessary pivotal movement of the eyes would require a rotary movement of the cross rod. In such case the cross rod could be pivotally mounted within a suitable bearing member as 29 which bearing member would in 15 turn be engaged by the toggle member 78 and strut 81. This form of mounting has some advantage in that the cross rod itself is not rigidly connected with the members which attach it in position within the doll head and 20 is therefore capable of a slight lateral movement sufficient to better enable the eye balls to properly locate themselves within the sockets of the doll head, the bearing as 31 provided by the member 29 being on this account preferably slightly larger than the 25 diameter of the cross rod.

In any case the toggle members 78 and 79, with their strut 81, constitute a supporting carrier for the eyes which carrier includes 30 part movable with respect to each other, and in a direction away from each other, to thereby engage against relatively opposite wall surfaces within a doll head for supporting the carrier, and the eyes are carried 35 upon a separate member mounted in the doll head by means of said supporting carrier, the arrangement being simple, practical and effective.

As many changes could be made in this 40 construction without departing from the scope of the invention as defined in the following claims, it is intended that all matter contained in the above description or shown in the accompanying drawings, shall be interpreted as illustrative only and not in a 45 limiting sense.

Having thus described my invention, what I claim as new and desire to secure by Letters Patent is:—

50 1. A supporting device for a doll's mechanism for movable elements, comprising toggle members engaging opposite walls of the doll head, a strut therefor and supporting the mechanism, and means co-operating between the members and the strut to spread 55 said members to increase their combined effective length.

60 2. A supporting device for a doll's mechanism for movable elements, comprising toggle members engaging opposite walls of the doll head and having spaced openings adjacent their pivoted ends, a supporting element carried by the members and supporting the mechanism, means co-operating with said 65 element and members to increase their com-

bined effective length, and means pivotally connecting said members and removably insertable into said openings.

3. A supporting device for movable elements of a doll's mechanism, comprising 70 toggle members engaging opposite walls of the doll head, a strut therefor, said strut and one of said members supporting said mechanism therebetween, and means cooperating with said strut and members simultaneously 75 to clamp said mechanism and to spread said members to increase their combined effective length.

4. A supporting device for movable elements of a doll's mechanism, comprising 80 toggle members engaging opposite walls of the doll head, a strut therefor having an end engaging one of said members, said strut and the other of said members supporting said mechanism therebetween, and means co-operating with said strut and said last named member for drawing said strut and last named member together to clamp the mechanism whereby said end will spread said members to increase their combined effective 85 length.

5. A supporting device for movable elements of a doll's mechanism comprising 90 toggle members engaging opposite walls of the doll head, a strut supporting said mechanism between itself and one of said members and having a stepped end engaging the other of said members, and a bolt co-operating with said strut and said first named member for drawing the latter and the strut together to 95 clamp the mechanism whereby said stepped end will spread said members to increase their combined effective length.

6. In a doll having movable eyes, in combination, a bridge member for the eyes, 100 toggle members engaging opposite walls of the doll head respectively, a slotted strut supporting said bridge member between itself and one of said members and having an end engaging the other member, and a bolt passing through said slot and co-operating with said first named member for drawing the latter and the strut together to clamp the mechanism, whereby said end will spread 105 said members to increase their combined effective length.

7. An eye set comprising a pair of eyes and a supporting carrier therefor, the carrier including a pair of toggle members movable with respect to each other to thereby engage 110 against oppositely facing surfaces within a doll head for retaining the carrier in position within the doll head, means for so moving said toggle members and a carrying member for the eyes also mounted upon said mentioned supporting carrier.

8. An eye set comprising a pair of eyes and a supporting carrier therefor, the carrier including a strut member and a pair of toggle members connected with the strut member 115 120 125 130

and movable with respect thereto and with respect to each other to thereby engage against oppositely facing surfaces within a doll head for retaining the carrier in position within the doll head, means for so moving said toggle members and a carrying member for the eyes supported by said supporting carrier by being engaged between said strut and one of said toggle members.

9. In an eye set, in combination, a bridge member having a pair of eyes carried thereby, a plurality of relatively movable supporting members, the bridge member being positioned between two of the supporting members, and manually operable means engaging said two mentioned supporting members to simultaneously draw said two supporting members against the bridge member and to adjust certain of said supporting members into engagement with the doll head wall.

10. An eye set comprising a pair of eyes and a supporting carrier therefor, the carrier including a first member and other members movable with respect to the first member and with respect to each other for engaging opposite wall parts of the doll head to retain the carrier within the head, a carrying member for the eyes mounted upon said first member, spring means for moving the mentioned relatively movable members into engagement with the wall parts of the doll head, and means manually operable independently of the spring means to force the mentioned relatively movable parts against the doll head parts.

35 In testimony whereof I affix my signature.
